MAGNETIC CIRCUIT COMPRISING ONE OR
MORE STACKED PLATES

Pieter Hendrik Johannes Brouwer, Eindhoven, Netherlands, assignor to Hartford National Bank and Trust Company, Hartford, Conn., as trustee

Application May 13, 1948, Serial No. 26,866
In the Netherlands June 5, 1947

5 Claims. (Cl. 171—209)

1

This invention relates to a magnetic circuit, for example for dynamos or motors, which comprises one or more stacked plates wherein each of the plates is provided with a number of poles arranged on edge and bent over with respect to the plate, the poles consisting of tags of each of the plates which are folded lengthwise so as to be U-shaped, in such manner that the ends of the limbs of the U are located on a surface of revolution.

The poles arranged on edge have the known advantage that the transition of the magnetic lines of force at the airgap—which is located at the said surface of revolution—from or towards the poles is not affected by the reluctance prevailing between the laminations.

The tags folded on their axis of length constitute, in mechanical respect, very rigid poles which are not required to be reinforced or otherwise secured. The term "axis of length of the tags" is to be understood to mean the axis located between the two edges of a tag, these edges constituting, after having been folded, the sides on edge of the poles.

The invention is particularly suitable for use with hub dynamos for bicycles, in which a very great number of poles is desirable.

In order that the invention may be more clearly understood and readily carried into effect, it will now be described more fully with reference to the accompanying drawing which represents embodiments thereof, given by way of example.

Figures 1 and 2 represent diagrammatically a plan view and a side view of part of the magnetic circuit according to the invention.

Figs. 3 and 4 show a magnetic circuit comprising three plates.

In Fig. 1 a plate is provided with a plurality of punched tags 2 which extend in a more or less tangential direction. The tags 2 are folded on their axis of length 3, so as to be U-shaped, in a direction away from the observer. The commencement of this folding operation is illustrated with reference to tag 4. The folding operation is preferably carried out to such an extent that the two inner surfaces 5 of the tag substantially coincide. Prior to, during or after the folding operation the tag is bent towards the observer, preferably at right angles to the plane of the drawing. In this manner poles 6 arranged on edge, are obtained, the ends 7 of the limbs of the U 8 thus being approximately located on a cylinder surface 9. An annular, permanent magnet comprising a number of magnet poles may be arranged to surround this cylinder surface, for ex-

2

ample to produce an E. M. F. in an annular coil (not represented for the sake of simplicity) which is arranged between the poles 6 and a cylindrical recess 10 in the central part of the plate 1. Fig. 2 is a side view of a pole 6 of the plate 1 and the central cylinder 10. In order to complete the coil circuit an exactly identical body comprising poles is introduced with the central cylinder into the annular coil in such manner that the poles of this second body are in interfitting relationship with the poles 6 of the plate 1, the central cylinder resting on the cylinder 10.

In Fig. 1 the ends of the limbs of the U of the pole 11 are bevelled by grinding as indicated at 12, so as to be parallel to the cylinder surface 9, in order to enlarge the pole surface adjacent the air gap. In addition this surface coincides better with the cylinder surface 9, so that the air-gap has the same width throughout.

Part of Fig. 1 shows another embodiment in which use is made of radial tags 13 which are folded together and bent to form poles 14 in the manner described above. This embodiment permits the use of a larger number of tags than in the case of tangential tags, so that the number of poles may also be increased.

If the bending over of the poles with respect to the plate 1 is effected through an angle (Fig. 2) of less than 90°, it is possible to obtain a pole 15, of which Fig. 1 is a plan view and Fig. 2 a side view. In every perpendicular section of this pole the limbs of the U become shorter and shorter according as the section approaches the free end of the pole. This means that the thickness of the pole decreases towards its end as appears from the side view of the pole 15 in Fig. 2. Such a pole may be formed either by folding the wedge-shaped tags or by grinding or turning off the superfluous material outlined by the dotted line in Fig. 2.

Figures 3 and 4 finally show one quarter part of a magnetic circuit for a bicycle hub dynamo, comprising three members shown in Figs. 1 and 2 which are arranged one within the other. The space between two successive poles 17 of one and the same member 18 is chosen to be so large that two poles 19 and 20 of the second and third member 21 and 22 respectively are adapted to be provided in between. The three central, cylindrical parts 23 to 25 also fit into one another.

The circuit thus built up has a pole width 25 which is double the thickness of the plate, the thickness of the remaining part of the magnetic circuit being three times the thickness of the plate.

The three plates are secured together, for instance with the aid of rivets 27 represented diagrammatically.

In the manner set out with reference to Figures 1 and 2 this coil-circuit also is completed by arranging a second body in reverse position.

It has finally proved very important to saw through the magnetic circuit at one point as shown at 28 in Fig. 3 by way of example, thus raising the power from 1.1 to 1.8 watts in a test circuit.

What I claim is:

1. A magnetic circuit arrangement for bicycle dynamos and the like, comprising a plurality of plates of magnetic material in stacked relationship, each of said plates having a plurality of pole-shoes, each of said pole-shoes comprising a tag-like projection of said plate bent over with respect thereto and in edge-wise relationship therewith and having a generally U-shape, the pole-shoes being arranged in such manner that the ends of the limbs of the U are located on a surface of revolution to provide a plurality of poles arranged on edge about the periphery of the plate.

2. A magnetic circuit arrangement for bicycle dynamos and the like, comprising a plurality of generally circular plates of magnetic material in stacked relationship, each of said plates having a plurality of pole-shoes extending tangentially from the periphery of the plate, each of said pole-shoes comprising a tag-like projection of said plate bent over with respect thereto and in edge-wise relationship therewith and having a generally U-shape, the pole-shoes being arranged in such manner that the ends of the limbs of the U are located on a surface of revolution to provide a plurality of poles arranged on edge about the periphery of the plate.

3. A magnetic circuit arrangement for bicycle dynamos and the like, comprising a plurality of generally circular plates of magnetic material in stacked relationship, each of said plates having a plurality of pole-shoes extending radially from the periphery of the plate, each of said pole-

shoes comprising a tag-like projection of said plate bent over with respect thereto and in edge-wise relationship therewith and having a generally U-shape, the pole-shoes being arranged in such manner that the ends of the limbs of the U are located on a surface of revolution to provide a plurality of poles arranged on edge about the periphery of the plate.

4. A magnetic circuit arrangement for bicycle dynamos and the like, comprising a plurality of plates of magnetic material in stacked relationship, each of said plates having a plurality of pole-shoes, each of said pole-shoes comprising a tag-like projection of said plate bent over with respect thereto and in edge-wise relationship therewith and having a generally U shape, each of said U-shaped tag-like projections having limbs which decrease in length toward the outer end of the tag-like projection, the pole-shoes being arranged in such manner that the limbs of the U are located on a surface of revolution to provide a plurality of poles arranged on edge about the periphery of the plate.

5. A magnetic circuit arrangement for bicycle dynamos and the like, comprising a plurality of annular plates having a narrow radial slit therein of magnetic material in stacked relationship, each of said plates having a plurality of pole-shoes, each of said pole-shoes comprising a tag-like projection of said plate bent over with respect thereto and in edgewise relationship therewith and having a generally U shape, the pole-shoes being arranged in such manner that the limbs of the U are located on a surface of revolution to provide a plurality of poles arranged on edge about the periphery of the plate.
